UNITED STATES PATENT OFFICE.

LESLIE R. N. CARVALHO, OF BROOKLYN, NEW YORK, ASSIGNOR, BY DIRECT AND MESNE ASSIGNMENTS, TO PARAGON METAL CAP COMPANY, OF BROOKLYN, NEW YORK, A CORPORATION OF NEW YORK.

PROCESS OF MANUFACTURING CLOSURES FOR RECEPTACLES.

1,274,138.

Specification of Letters Patent. Patented July 30, 1918.

Application filed August 29, 1913. Serial No. 787,311.

To all whom it may concern:

Be it known that I, LESLIE R. N. CARVALHO, residing at Brooklyn, in the county of Kings and State of New York, have invented certain new and useful Improvements in Processes of Manufacturing Closures for Receptacles, of which the following is a specification.

This invention relates to the art or process of manufacturing closures for receptacles, such as bottles and the like, and the particular object of the invention is to provide a new and improved process for producing rigidly formed closures whereby such closures may be built up from a plurality of separately formed sheet-metal pieces, to the end that the manufacturer of the closures may be materially cheapened and at the same time result in an attractive and efficient article.

A further object is to provide a new and improved process of the character described, such that metallic caps may be formed from sheet metal with a minimum waste of material and whereby previously coated or decorated sheet metal may be formed into closures without injury or removal of such coating or decoration.

A further object of the invention is to provide a process such that the means to be employed for the attachment of the closure to the receptacle is formed on said closure simultaneously with the fastening together of the pieces of sheet metal which go to make up said closure.

A still further object of the invention is to provide a process of producing the closure whereby the steps thereof are so arranged and related that a cylindrical portion and a separate cap member may be connected together in such a manner that a wedging action is always present between said parts to retain said parts in rigid relation to each other.

Referring to the drawings wherein are illustrated the various steps entering into this process, and wherein are diagrammatically illustrated sufficient mechanism to render the several steps clearly understandable;

Figure 1 indicates a blank of material, preferably sheet tin or the like, from which the smaller pieces may be cut for forming the parts of this closure, the blank being

shown partly coated with a lacquer or the like and illustrating in dotted lines the shape of pieces to be cut therefrom.

Fig. 2 is a transverse sectional view through the sheet of material shown in Fig. 1 for positively illustrating the lacquer or other coating upon one of its surfaces, it being understood, of course, that the coating may be applied also to the other surface, if desired.

Fig. 3 illustrates the small rectangular piece of metal from which the cylindrical portion of the closure is to be formed, this piece of metal being presumably one of those outlined by dots in Fig. 1 and being shown on an enlarged scale.

Fig. 4 is a perspective view for illustrating several of the steps of the process through which the blank shown in Fig. 3 progresses in the formation of the cylindrical or flange portion of the closure, these steps being shown in connection with a mandrel or horn upon which the steps are applied.

Fig. 5 illustrates an end view of the cylinder formed as shown in Fig. 4, this view clearly illustrating the type of joint employed for connecting the juxtaposed edges of the blank.

Fig. 6 illustrates a perspective view of a cylinder after having passed through the steps indicated in Fig. 4.

Fig. 7 illustrates a perspective view of the disk portion of the closure;

Fig. 8 illustrates a transverse sectional view of the cylindrical portion of the closure for more positively indicating the shape of said part as shown in Fig. 6, and this view also indicating a further step of introducing the disk, shown in Fig. 7, into the cylinder;

Fig. 9 is a view similar to Fig. 8, but indicating the cylinder and disk applied upon a mandrel or horn and being held thereto for maintaining the disk closed against the inner surface of the flange of the cylinder, this view also illustrating the means for impressing the threads into the cylinder and for impressing the longitudinal reinforcing ribs which also lock the disk rigidly within the cylinder;

Fig. 10 is a transverse sectional view of the completed closure as the same would be expelled from the mandrel or horn, shown

in Fig. 9, the view being considerably enlarged for more clearly illustrating the manner in which the ends of the longitudinal reinforcing ribs formed in the step indicated in Fig. 9 engage against the flange portion of the disk for wedging the disk against the flange of the cylinder, and for corrugating the flange portion of the disk to more effectively coöperate with the ends of the reinforcing ribs to lock the disk in position and to retain the disk against any possible relative rotary movement within the cylinder; and

Fig. 11 is a perspective view of a completed closure.

Referring to the drawings for a more detailed description of the process illustrated and of the mechanism employed in carrying these steps to completion, the reference character L indicates the sheet of material from which the parts of the structure are to be formed. This may be a sheet of ordinary tin, and owing to the fact, as will be presently apparent, that little or no drawing of the metal is required in the formation of the closure, the material may be of a decidedly lighter and cheaper weight than has been heretofore employed. This material may be polished or may be provided with lacquer or any similar paint or coating upon one or both of its surfaces, as desired, the lacquer or the like being applied while the sheet presents a large and convenient surface for receiving the same.

From this sheet of prepared material the parts may be cut, as indicated by dotted lines at 2 and 3.

The parts 2 are rectangular in shape and, after being cut from the sheet L are coped away at opposite corners, as at 4, to form the blank G from which the cylinder or flange portion of the closure is formed, as shown in Fig. 3.

The blank G is to be bent upon itself into cylindrical form and seamed together by its opposite ends. To accomplish this I preferably provide a mandrel or horn 5 upon which the various steps of this part of the process may take place, suitable means, of course, being employed for engaging portions of the blank to effect the different steps.

The mandrel 5 is of a diameter equal to the inner diameter desired for the cylinder, and it is provided with a longitudinally extending groove 6 within which the projection formed by the seam may extend after the seam is made. The first step, as indicated at I at the extreme left of Fig. 4, is that of bending the blank G about the mandrel. The next step shown at II, is that of bending up the end portions of the blank, as at 7. The next step, as at III, is that of bringing the ends of the blank together so that the portions 7 will engage behind each other. The next step as at IV, is that of

folding down the portions 7 to complete the seam as shown at 8. The shape of the seam is best seen in Fig. 5.

The cylinder is now ready to be operated upon for forming the inturned flange at 70 its end, as indicated at 9 in Fig. 6 and elsewhere.

During the successive steps of the operation of forming the cylinder, the cylinder is preferably advanced along the length of the 75 mandrel, as illustrated in Fig. 4, but these steps may obviously be impressed while the blank stands at one position upon the mandrel, if desired. When the seam is complete and the cylinder ready to receive the flange 80 9, it is required that the cylinder be then at a position, as at V in Fig. 4, so that the portion from which the flange is to be formed shall project beyond the end of the mandrel.

As illustrated in Fig. 4, the mandrel is 85 formed with an annular groove 10 near its right hand end and a pair of gates 11 is provided having semi-circular pockets 12 formed therein for permitting the movement of the gates to a position within the groove 90 10, as shown by the dotted lines. The gates 11 are adapted, when in position engaging in the groove 10, to form a positive barrier against which the left hand end of the cylinder may engage when the cylinder is in 95 position with its right hand end projecting the desired amount beyond the end of the mandrel. The gates are preferably arranged to open, as illustrated in full lines, for permitting movement of the cylinder 100 therebetween toward the end of the mandrel and the gates are then closed behind the cylinder, after which a plunger die 13 is forced against the projecting annular edge 105 of the cylinder to turn in said annular portion of the cylinder.

The die is provided with an inclined annular surface 14 for engaging with the outer edge of cylinder and, as the die is pressed toward the end of the mandrel this inclined 110 portion 14 will cause the entire projecting portion of the cylinder to be bent inwardly to form the flange 9.

It will be understood that the coped out portions 4, as illustrated in Fig. 3, are intended to provide an unseamed portion at the end of the cylinder so that when the flange is inturned there will be no seam in the flange. This of course, will result in a smooth flange of uniform thickness.

In Fig. 3 the dotted lines 15 indicate the lines upon which the ends of the blank are bent to form the seam, and the dotted line 16 indicates the line upon which the end of the cylinder is bent to form the flange 9.

After completing the cylinder, as in Fig. 6, the next step of the process is to provide the disk or cover portion H of the structure shown in Fig. 7, and insert the same within the cylinder. This portion may be cut from 130

the same, or a similar, sheet of lacquered metal L, as illustrated by the dotted lines at 3 in Fig. 1. When cut from the sheet L the disk is of a slightly larger diameter than 5 the internal diameter of the cylinder, but before inserting it within the cylinder, it is subjected to a simple pressing operation to bend or flange down the marginal portion of the disk to form a diagonally projecting resilient flange 17 of just sufficient 10 diameter to fit snugly between the walls of the cylinder, as shown in Fig. 8.

The next step in the process is to introduce a horn 18 into the cylinder to hold 15 the disk against the flange 9 of the cylinder. The horn is cylindrical and is formed with threads 19 and depressions 20 so as to comprise a female die for coöperating with a male die 21.

20 The next step of the process is to bring the die 21 against the outer surface of the cylinder and to rotate the horn 18 and die 21, while the die 21 is pressing against the cylinder, so as to press the material of the 25 cylinder into the shapes determined by the dies, namely to form the threads and the reinforcing ribs or finger-grip parts. The depressions 20 on the horn, and the projecting portions 22 on the die 21 for forming 30 the reinforcing ribs or corrugations 24 are so disposed relatively to the end of the horn, and consequently to the flange 17 of the disk H, that when these parts of the dies are forced toward each other, they not only 35 press in portions of the cylinder but they also spring in the flange 17, as clearly seen at 23 in Fig. 10.

The next and final step of the process is to withdraw the horn 18 from within the 40 cylinder. This may be accomplished by actually moving the horn from within the cylinder or by moving the cylinder from its position about the horn. In the latter instance the head 25 may be removed and 45 a plunger 26, extending through the horn, be employed for thrusting the finished article off of the horn.

The portions 23 of the resilient diagonal flange 17, engaging against the relatively inclined surface portions formed at the ends 50 of the corrugations 24 of the walls of the cylinder at a sharp angle due to the inclination of the flange, constantly exert a considerable pressure against said inclined surfaces tending to wedge or cam the cover 55 into tight contact with the inner surface of the flange 9 of the cylinder in the finished article. By this means the raw edge of the flange 9 is protected from exposure to the 60 contents of the bottle, while the raw edge of the flange 17 is partially covered and concealed.

The die 21 is preferably a rotary die so 65 that no dragging or rubbing action will take place upon the surface of the cylinder. The

operation of forming the threads and the corrugations or reinforcing ribs 24 is effected by a simple pressing operation and is almost entirely free from any drawing or rubbing of the metal, such as would deface or mutilate the surface coating upon the metal. This is as true of the interior as of the exterior of the cylinder. In the event of a coating being applied to both sides of the blank employed, one side being for ornamentation and the other side being for sanitary purposes, the interior or sanitary coating will not be injured.

Attention may be also directed to the fact that in case it is desired to apply a special 80 ornamentation to the disk portion of the closure, this may be done without mutilation or defacement, not only in the steps of the process described, but in any ordinary handling to which the finished article may 85 be subjected, for the reason that the projection of the flange 9 beyond the surface of the disk will serve to relatively inset said surface and thereby protect such ornamentation against defacement by contact with foreign objects. This advantage is particularly 90 noticeable by reason of the relatively small diameter of the closure.

It will be understood that various changes 95 may be resorted to in the manner of carrying out the several steps of the process, in the nature of the mechanism employed in carrying out the steps, and in the material and structure of the finished article, without departing from the spirit and scope of my 100 invention; and hence I do not intend to be limited to the specific details herein shown and described except as they may be set forth in the claims.

Having thus described my invention, what 105 I claim as new and desire to secure by Letters Patent, is:—

1. The process of producing a receptacle closure, which consists in providing a sheet of metal, coating said metal with a suitable 110 lacquer, separating a portion of said metal from said sheet to form a blank, forming said blank into a cylinder, bending the material of said cylinder at one end thereof inwardly to form a flange, inserting a cover 115 member within said cylinder to engage said flange, and then pressing inwardly the material of said cylinder between said cover member and the opposite end of the cylinder so as to retain said cover member fixed between said flange and the inwardly pressed portions of the cylinder.

2. The process of producing a receptacle closure, which consists in providing a suitable blank of metal, forming said blank into 125 a cylinder, forming an inwardly projecting flange at one end of said cylinder, inserting a cover member within said cylinder into engagement with said flange, and then pressing inwardly portions of the material of 130

said cylinder to simultaneously lock the cover member against said flange and form threads adjacent the open end of the cylinder.

5 3. The process of producing a receptacle closure, which consists in providing a sheet of metal, cutting a rectangular blank from said sheet of metal, forming said blank into a cylinder, turning in one end of said cylinder to form a flange at the end of said cylinder, providing a disk-shaped blank, turning down a marginal portion of said disk-shaped blank to form a cover part having a resilient annular flange, inserting said cover part into 10 said cylinder to engage the flange of said cylinder so that the flange of the cover part projects away from the flange of the cylinder, and subsequently pressing in portions of the material of the cylinder to engage the 15 flange of the cover part to lock the cover part against the flange of the cylinder.

4. The process of producing a receptacle closure, which consists in providing a sheet of metal, cutting a rectangular blank from 25 said sheet of metal, forming said blank into a cylinder, turning in one end of said cylinder to form a flange at the end of said cylinder, providing a disk-shaped blank, turning down a marginal portion of said disk-shaped blank to form a cover part having 30 a resilient annular flange, inserting said cover part into said cylinder to engage the flange of said cylinder so that the flange of the cover part projects away from the flange of the cylinder, and subsequently pressing in portions of the material 35 of the cylinder spaced from the flange of the cylinder to form a relatively inclined surface interiorly of the cylinder engaging the resilient edge portion of the flange of the cover part to spring said edge portion of the flange of the cover part inwardly and thereby produce a constant force wedging the cover part against the flange of the cylinder.

5. The process of producing a receptacle closure, which consists in providing a cylinder, turning in one end of the cylinder to form a flange at said end of the cylinder, inserting a flanged cover part within said cylinder to engage the flange of the cylinder, and then pressing the material of the cylinder to simultaneously form said material into longitudinally extending reinforcing ribs 50 and annually extending threads, the longitudinally extending ribs providing relatively inclined surface portions interiorly of the cylinder at their ends engaging the annular edge of the flange of the cover part to spring said edge inwardly and thereby produce a constant force wedging the cover part against the flange of the cylinder.

6. The process of producing a receptacle closure, which consists in providing a sheet 65 of metal, coating said metal with a suitable

lacquer upon one of its surfaces, separating a portion of said metal from said sheet to form a blank, forming said blank into a cylinder with its lacquered surface outermost, bending the material of said cylinder 70 at one end thereof inwardly to form a flange, inserting a cover member within said cylinder to engage said flange, and then pressing inwardly upon the lacquered surface of the material of said cylinder between said 75 cover member and the opposite end of the cylinder so as to form inwardly-projecting parts engaging the cover member to force the cover member against the flange of the cylinder.

7. The process of producing a receptacle closure, which consists in providing a sheet of metal, coating one surface of said sheet of metal, cutting a rectangular blank from said coated sheet of metal, providing a mandrel, bending said blank about said mandrel, seaming together the ends of said blank to form a cylinder about said mandrel, moving said cylinder along said mandrel so that a portion of one end of said cylinder projects beyond the end of said mandrel, providing a barrier to prevent return movement of the cylinder along the mandrel, striking in the annular edge of the projecting portion of the cylinder to form 90 an inturned flange at the end of the cylinder, removing the cylinder from the mandrel, inserting a flanged cover part into the cylinder with its flange projecting away from the flange of the cylinder and engaging the walls of the cylinder, and subsequently pressing in portions of said cylinder and portions of the flange of said cover part to lock said cover part against the flange of the cylinder.

8. The process of producing a flanged cylinder, which consists in providing a suitable blank, providing a suitable mandrel, bending said blank about said mandrel, seaming together the ends of said blank to form a 100 cylinder about said mandrel, moving said cylinder along said mandrel so that a portion of one end of said cylinder projects beyond the end of said mandrel, providing a barrier to prevent return movement of the cylinder along the mandrel, and then simultaneously bending the whole annular projecting portion of said cylinder over the end of said mandrel.

9. The herein described process of producing a receptacle closure, which consists in providing a cylinder of sheet-metal, forming a flange at one end of said cylinder, positioning a cover member into engagement with said flange, and then in a single operation locking together portions of said cylinder and cover member and forming threads upon said cylinder.

10. The herein described process of producing a receptacle closure, which consists 130

in providing a cylinder of sheet metal, forming a flange at one end of said cylinder to partially close said end, inserting a cover member into said cylinder from the opposite 5 end thereof and moving said cover member into engagement with said flange, and subsequently applying pressure to change the shape of portions of said cylinder to provide parts interlocking with said cover member.

11. The herein described process of producing a receptacle closure, which consists in providing a cylinder of sheet metal, forming a flange at one end of said cylinder to 15 partially close said end, inserting a cover member into said cylinder from the opposite end thereof and moving said cover member into engagement with said flange, and subsequently applying pressure to form stiffening 20 ribs upon the cylinder disposed to serve as means for locking the cover member against the flange.

12. The herein-described process of producing a receptacle closure, which consists in providing a cylinder of suitable material, bringing a cover member into engagement with one end portion of said cylinder, and then operating upon said cylinder and cover member to perform the double functions of 30 locking the cover member to the cylinder and forming portions of the cylinder with parts to retain the completed cover upon a receptacle.

13. The process of producing a receptacle 35 closure, which consists in providing a cylinder, turning in one end of the cylinder to form a flange on said end of the cylinder, inserting a flanged cover part within said cylinder to engage the flange of the cylinder, 40 and then pressing the material of the cylinder to form longitudinally extending ribs in the cylinder, having relatively inclined surface portions at their ends engaging the flange of the cover part and wedging the 45 cover part against the flange of the cylinder.

14. The process of producing a receptacle closure, which consists in providing a cylinder having an inturned flange at one end, inserting a cover member within the cylinder 50 to engage the flange of the cylinder, and then pressing inwardly a portion of the material of the cylinder between said cover member and the opposite end of the cylinder 55 so as to form inwardly projecting parts engaging the cover member and forcing the cover member against the flange of the cylinder.

15. The herein described process of producing a multi-part lacquered receptacle 60 closure, which consists in providing a blank of suitable material, applying a coat of lacquer to one surface of said blank, bending said lacquered blank to form a cylinder, positioning a cover part in engagement with one end of the cylinder, and then pressing 65

upon the lacquered cylindrical surface of the cylinder to bend the material of the cylinder and thereby provide portions to retain the cover part within the cylinder.

16. The herein described process of producing a flanged cylinder, which consists in providing a suitable blank, bending said blank about a suitable mandrel so that portions of said blank overlap each other to form a cylinder upon said mandrel, connecting the lapping portions of the blank together to complete the cylinder, and then bending a portion of the cylinder over the end of the mandrel to form a flange upon the cylinder.

17. The herein-described process of producing a multi-part lacquered sheet-metal receptacle closure, which consists in coating both of the surfaces of a piece of sheet metal with lacquer or the like, cutting a suitably shaped blank from said lacquered sheet-metal, bending said blank into cylindrical form, joining the meeting edges of said blank together by a seam which covers and conceals the exposed raw edges of the sheet-metal formed in cutting the blank from the sheet whereby to provide a body part for the closure which is lacquered upon both its inner and outer surfaces throughout, the lacquer being carried into the seam to protect the parts thereof against likelihood of corrosion, then cutting a second suitably shaped blank from said lacquered sheet-metal to constitute a top part for the closure, positioning said top part adjacent one end of said body part to close said end, and then operating upon said body part and upon said top part to lock said top part within said body part.

18. The herein-described process of producing a multi-part lacquered sheet-metal receptacle closure, which consists in coating both of the surfaces of a piece of sheet metal with lacquer or the like, cutting a suitably shaped blank from said lacquered sheet metal, bending said blank into cylindrical form, joining the meeting edges of said blank together by a seam which covers and conceals the exposed raw edges of the sheet metal formed in cutting the blank from the sheet whereby to provide a body part for the closure which is lacquered upon both its inner and outer surfaces throughout, the lacquer being carried into the seam to protect the parts thereof against likelihood of corrosion, then cutting a second suitably shaped blank from said lacquered sheet metal to constitute a top part for the closure, positioning said top part in engagement with one end of said body part to close said end, and then providing means at said end of the body part to cover and conceal the exposed raw edge of the metal at said end formed in cutting at least one of said parts from said lacquered sheet.

125
130

19. The herein-described process of making a receptacle closure, which consists in bending a strip of sheet-metal into cylindrical form, bending the meeting edges of said strip to form an interfolded seam in which the edge surfaces of said meeting edges are covered and concealed, positioning a cover part within the upper end of the cylinder, operating upon said cylinder and cover part to lock said cover part within said cylinder, and then pressing upon said sheet-metal to form two sets of corrugations therein, one set being disposed adjacent the lower end of the cylinder and extending circumferentially thereof, said set of corrugations constituting a continuous thread extending across and indenting the interfolded parts of the seam to reinforce said seam, and the second set of corrugations extending longitudinally of the cylinder from said first set toward the upper end of the cylinder. 40
20. The herein-described process of making a receptacle closure, which consists in bending a strip of sheet-metal into cylindrical form, bending the meeting edges of said strip to form an interfolded seam, arranging a cover part at one end of the cylinder, and then forming threads upon the cylinder which serve to lock the interlocking portions of the seam against relative longitudinal movement. 45
21. The process of producing a receptacle closure, which consists in providing a blank of sheet-metal, forming said blank into a cylinder, providing a second blank of sheet- 50
- metal circular in form, positioning the second blank within the cylinder adjacent one end thereof, bending the adjacent portion of the cylinder into engagement with the periphery of the second blank for securing the parts together, and providing the said cylinder with a screw-thread for engagement with a receptacle, said thread also serving to lock the meeting portions of the seam against relative longitudinal movement. 55
22. The process of producing a receptacle closure, which consists in providing a blank of sheet-metal having an anti-corrosion coating, bending said blank into cylindrical form, joining the meeting edges of said blank by a seam which covers and conceals the said edges, providing a second blank of sheet-metal circular in form, said blank also having an anti-corrosion coating, positioning the second blank within the cylinder adjacent one end thereof, bending the adjacent portion of the cylinder into engagement with the periphery of the second blank for securing the parts together, and providing the said cylinder with a screw-thread for engagement with a receptacle, said thread also serving to lock the meeting portions of the seam against relative longitudinal movement. 60
